REFRIGERATOR LIGHT OUTSIDE OF COLD ZONE

Filed Sept. 4, 1936

UNITED STATES PATENT OFFICE

2,153,851

REFRIGERATOR LIGHT OUTSIDE OF COLD ZONE

Enoch Swedman, St. Paul Minn., assignor to
Seeger Refrigerator Company, St. Paul, Minn.,
a corporation of Minnesota

Application September 4, 1936, Serial No. 99,387

1 Claim. (Cl. 240—4)

This invention relates to refrigerator light positioned outside of the cold zone of the refrigerating chamber, so that the light which is designed to illuminate the cold chamber when the door of the same is opened, does not affect the cold units within the refrigerating chamber. Heretofore refrigerators have been built with electric lights in the cold zone or chamber and a certain amount of heat was dissipated from the electric light into the cold zone. This has been overcome with this refrigerator light which is positioned outside of the cold zone so that it does not in any manner interfere with the refrigerated chamber.

Further, this invention includes a means of positioning the electric light in a portion of the refrigerator body which acts to shield the eyes of the observer when the refrigerator is open, because the light is recessed into the doorway below the line of vision. In this position, the electric light is adapted to shine directly into the cold zone of the refrigerating chamber when the door of the same is open.

Further, the invention includes a switch arm means which extends into a position so that the arm engages against the inside of the surface of the door when the door is closed to shut off the electric light and when the door is opened the switch arm automatically moves into position to light the electric light. By forming the arm in this manner which controls the switch of the electric light, the enamelled sheathing which covers the door will not be marked or scratched by the switch arm so as to injure the outside finish of the refrigerator door. In old forms used heretofore, this was an objectionable feature.

Suitable gasket sealing means is positioned between the door of the cold zone chamber and the insulating body forming the housing for the cold zone, thus to confine the cold zone of the refrigerator with a nonrefrigerated space about the door. In this nonrefrigerated space and entirely outside of the cold zone, the electric light is positioned, concealed by recessing the same into the body of the refrigerator, thereby keeping any heat from the light outside of the cold zone and forming a shelf under which the light is positioned in the doorway which acts as an eye shield.

In the drawing forming part of this specification:

50 Figure 1 illustrates a refrigerator with the door of the same open to expose the cold zone or refrigerating chamber.

Figure 2 is a cross-sectional detail of a portion of the body and door of the refrigerator, showing 55 the position of the electric light in the body of

the refrigerator, which is recessed therein, and showing the operating switch arm, together with the gasket means between the refrigerator body and the door to seal the cold zone.

Figure 3 is a bottom view of an electric light 5 as it would appear under the shelf formed by the projecting portion of the top of the refrigerator, and showing the light outside of the cold zone.

In the construction of the refrigerator A, the upper portion of the refrigerator projects in a 10 shelf-like part 10 above the door B so that when the electric light 11 is recessed into the under side of the shelf portion 10, the rays of the light are not visible to the user of the refrigerator, because the light is under the shelf portion 10 as 15 illustrated in Figure 2, and the light may shine into the cold zone 12 of the refrigerator A without blinding the person opening the door of the same.

The electric light 11 is recessed into the opening 13 on the under side of the shelf portion 10 20 and is adapted to be operated by the switch arm 14 which has a projecting portion 15 depending from the shelf 10 and positioned so that when the edge of the door B moves into closed position to close the cold zone 12 of the refrigerator A, 25 the end 15 of the arm 14 is engaged by the inner surface of the edge of the door B operating the switch which turns off the electric light 11.

The door B is provided with a marginal gasket C which extends about the door in a manner to 30 provide a sealing means so as to close the cold zone when the door B is shut. The gasket C is formed with a hollow outstanding rib portion 16 which compresses when the door B is closed against the surface 17 to tightly seal the cold 35 zone 12.

The door B is provided with suitable means for hinging the door to the body of the refrigerator A, and a suitable lock for holding it closed. In the construction of refrigerators of this character, an enamelled metal sheathing covers the outside and extends to the shoulder against which the door gasket C engages. With the arm 14 formed with a depending portion 15 which engages against the corner or edge 18 of the door 45 B, only a slight contact is necessary and therefore the door sheathing will not be marked or marred by the engagement of the switch arm end 15. When the door opens, the switch arm moves in the slot 19 and turns on the electric 50 light 11.

The door B is fixed to the refrigerator so as to provide a space about the same so that when the gasket C closes the cold zone 12, there is provided around the door a nonrefrigerated space 55

which is entirely outside of the cold zone. By placing the light 11 in this space, any heat from the electric light 11 is not transmitted into the cold zone 12, and this is highly important in refrigeration where it is desirable to maintain all the cold units within the cold zone and where it has been found for other reasons, undesirable to have an electric light within the cold zone of the refrigerator.

10 Thus a desirable construction is provided in the refrigerator A, wherein the electric light is placed outside of the cold zone and is adapted to be operated by the opening and closing of the door, and where the light is inconspicuous to the observer, 15 providing a refrigerator construction of a neat design and having greater efficiency than in the old forms of refrigerators where the lights were placed inside of the cold zone. The light 11 is of a unitary character and extends along as illustrated in Figure 3, under the shelf 18, and by

being placed outside of the cold zone is not subject to the moisture or dampness of refrigeration, either in the switch mechanism or the electrical connections.

I claim:

10 A refrigerator including a body portion having a door opening therein, inner and outer metallic coverings for said body portion, an overhanging portion in said body portion forwardly of said door opening enclosed by said outer sheathing, a metallic reflector connected directly to said outer sheathing whereby heat in said reflector may be dissipated by said outer sheathing, a light means in said reflector arranged to illuminate the interior of said refrigerator body portion, a refrigerator door in said opening, and means actuated by movement of said door for controlling said light.

15 ENOCH SWEDMAN. 20
